CRIBBAGE BOARD OR SIMILAR ARTICLE

Alban J. Carlson, Sherman Oaks, Calif.

Application April 27, 1953, Serial No. 24,703

Term of patent 14 years

(CL. D34—5)

To all whom it may concern:

Be it known that I, Alban J. Carlson, a citizen of the United States, residing at Sherman Oaks, in the county of Los Angeles and State of California, have invented a new, original, and ornamental Design for a Cribbage Board or Similar Article, of which the following is a specification, reference being had to the accompanying drawing, forming a part thereof.

In the drawing:

Figure 1 is a perspective view of a cribbage board or similar article in open position and showing my new design;

Figure 2 is a side elevational view of the cribbage board or similar article of Figure 1 in closed position; and

I claim:

The ornamental design for a cribbage board or similar article, as shown and described.

ALBAN J. CARLSON.
